[57] CLAIM

The ornamental design for a handle for kitchen tools, as shown and described.

DESCRIPTION

FIG. 1 is a perspective view of a handle for kitchen tools showing my new design;

FIG. 2 is a top plan view thereof;

FIG. 3 is a side elevational view thereof the opposite side being identical;

FIG. 4 is a bottom plan view thereof;

FIG. 5 is a front elevational view thereof;

FIG. 6 is a rear elevational view thereof;

FIG. 7 is a cross-sectional view taken along line 7—7 of FIG. 2; and,

FIG. 8 is a cross-sectional view taken along line 8—8 of FIG. 2.

The blade is shown in broken lines for illustrative purposes only.
